UNITED STATES PATENT OFFICE

2,553,211

CONTROL MEANS FOR SEWING MACHINES

Aage Rothenborg, Hellerup, Denmark, and Allan Herman Eriksson and Bengt Arne Magnusson, Huskvarna, Sweden, assignors to Husqvarna Vapenfabriks Aktiebolag, Huskvarna, Sweden, a corporation of Sweden

Application January 22, 1946, Serial No. 642,642
In Sweden December 29, 1944

7 Claims. (Cl. 112—158)

1

In certain kinds of work, such as embroidery work, which are performed by means of zig-zag sewing machines, it is desirable that both hands be free as far as possible to keep and guide the work. The present invention has for its object to provide an arrangement facilitating such operations, the same being devised to permit the performance of certain operating movements by the knee of the operator.

A substantial characteristic feature of the invention resides primarily in the combination of an operating member adapted to be actuated by the knee of the operator with a coupling member adapted to be coupled at will, to certain operating means, such as the lifting means of the presser foot, when this is desired, or to means for the control of the needle bar amplitude, when this is desired. Consequently, the invention permits not only the governing of a certain movement with the aid of the knee, but also the selection of an arbitrary one of two or more different operating movements and their coupling to the operating member through the actuation of a coupling member. The operating movements primarily brought into consideration refer to the movement of the presser foot bar at the lifting of the presser foot and to the actuation of the zig-zag mechanism for the control of the width of the zig-zag seam (the amplitude of the oscillatory movement of the needle bar).

Further features characteristic of the invention and advantages inherent therein will appear from the following description of two embodiments illustrated in the accompanying drawing, said embodiments being intended to serve as an elucidating example. The drawing shows parts of a zig-zag sewing machine with a device according to the invention mounted thereon, Figs. 1-3 of one embodiment, Fig. 1 being a front elevation, Fig. 2 a plan view, and Fig. 3 an end view, partly in a vertical cross section through the housing of the sewing machine, and Figs. 4-7 of the other embodiment, Fig. 4 showing a front elevation of a zig-zag sewing machine provided with the operating device, and Fig. 5 being a vertical section on line A—A in Fig. 4. Figs. 6 and 7 show a detail in section on lines C—C and D—D in Fig. 5, respectively. Figs. 8 and 9 are cross sections of a detail of the control means showing two different positions of the parts.

As shown in Figs. 1-3, the operating member may consist of a bell crank lever 3 provided with a supporting plate 1 for the knee 2 of the operator, said bell crank lever being mounted on a fixed stud 4 and connected with the one end of a

2

link rod 5, the other end of which is pivotally connected to a supporting member or an arm 6 constituting the one lever arm of a bell crank lever, the other arm of which is designated by 7. The bell crank lever 6, 7 is mounted concentrically to a shaft 8, preferably on a bearing bushing 9 arranged thereon, said bushing being fitted into the wall 10 of the housing of the sewing machine. The shaft 8 is coupled, by means of arrangements not shown in the drawing, to the mechanism effecting the zig-zag movement of the sewing machine, in a manner such that the amplitude of the zig-zag movement or the width of the seam is controlled by a turning movement of said shaft. An example of such a mechanism will be found in the co-pending patent application Serial No. 648,183, filed February 16, 1946.

An arm 11 is mounted concentrically with the shaft 8, preferably on the bushing 9, said arm being connected through a link rod 12 to the one arm of a bell crank lever 15 mounted on a fixed stud 14, the other arm of said bell crank lever cooperating with a lifting block 16 coupled to the presser foot bar 17.

The operating member may be coupled to the shaft 8 or to the described mechanism for raising the presser foot bar, said coupling being effected by means of a coupling member consisting of a carrier 19 mounted on a stud 18 in a slot in the arm 7. The carrier 19 is made as a double-armed lever, one arm of which is provided with a carrier abutment 20, which may be brought into engagement with a recess 21 in a flange 22 secured on the shaft 8, and the other arm of which has a carrier abutment 23 for cooperation with a slot 24 in the arm 11 pertaining to the lifting device of the presser foot bar.

The device operates in the following manner: According to Figs. 3 and 8, the upper arm of the carrier 19 is depressed, so that the abutment 23 is introduced into the slot 24 of the arm 11, while the abutment 20 on the lower arm of the carrier is out of engagement with the recess 21 in the flange 22. If the operating member is actuated by the supporting plate 1 being moved by the knee 2 to the left in Fig. 1, the rod 5 will be displaced upward by the bell crank lever 3, so that the bell crank lever 6, 7 is turned in a counter-clockwise direction. The carrier 19 then carries the arm 11 along with it by means of the abutment 23, said arm then pulling the link rod 12 to the left, whereby the bell crank lever 15 is turned in a counter-clockwise direction and moves the lifting block 16 so as to press the rod

17 upward. The movement is counteracted by the spring (not shown) of the presser foot bar, and consequently all of the parts of the arrangement return to the initial position, when the supporting plate is released.

If it is desired to adjust the amplitude of the zig-zag movement, the lower arm of the carrier is depressed, so that the abutment 20 thereon is brought into engagement with the recess 21 (the shaft 8 may be turned by means such as a handle 8a in Fig. 5, in such manner that the recess 21 is brought opposite the abutment 20), whereby the arm 7 is coupled to the shaft 8. At the same time the abutment 23 on the upper arm of the carrier is moved out of the slot 24, so that the connection with the lifting device of the presser bar is interrupted. The shaft 8 can now be turned with the aid of the operating device by the supporting plate being actuated by means of the knee, whereby the width of the seam is varied.

The invention is not limited to the details illustrated in Figs. 1 to 3, but includes many variations and modifications. For example, a somewhat simpler construction can be obtained by using the embodiment illustrated in Figs. 4 to 7, in which the coupling member is formed as a link connection between the control operating means and the lever for the presser foot lifting member.

As illustrated in Figs. 4 to 6 5 designates the link rod which is included in the operating device which comprises a lever system of the type illustrated in Fig. 1, the upper end of the link rod being connected with the one end of a double-armed lever 6'. The lever is mounted concentrically with a regulating shaft 8' pertaining to the means for regulating the amplitude of the needle bar and the width of the seam, said lever being carried on the bushing or sleeve 9' which is rotatably arranged on said shaft and rotatably fitted into a bearing 47 in the wall 10 of the housing of the sewing machine. The presser foot bar 17 may be raised with the aid of the lever 15' which is pivotally mounted on a stud 15a in the housing of the machine, one arm of said lever being in engagement with a lifting block 16' arranged on the presser foot bar. One end of a link 19' is swingably mounted on a stud 18' on the upper arm of the supporting member or lever 6' in the figure, the other end of said link forming a connection with one or the other of the members to be operated, said connection being adapted to be released. According to the drawing, the link 19' is formed to a hook, which in the position shown by full lines grasps about the projecting end portion 15b of the lever 15', but which is adapted to be swung rearward, so that a shoulder 19a on the edge thereof is brought into engagement with a projection 44 on that end of the sleeve 9' which projects from the machine housing (dotted lines in Fig. 4). By the fact that the hook is swung over in this manner, the connection of the operating member with the presser foot bar is interrupted, and instead the operating member is coupled to the means for regulating the seam width.

The width of the seam is regulated manually by turning the shaft 8' by means of a handle 8a, when is secured on the shaft 8'. When operation is effected by the knee, the turning movement of the sleeve 9' is transmitted to the shaft 8' through a friction coupling consisting of a spring plate 40, which is non-rotatably secured to the end of the shaft 8' and bears with its edge on the end surface of the sleeve 9'.

A return spring 43 inserted between the bottom of the machine frame, on the one hand, and a clamping ring 9a surrounding the sleeve, on the other hand, tends to keep the sleeve 9' in an angular position, where a pair of abutments 45 on the end of the sleeve 9' are in engagement with corresponding fixed abutments 46 on the stationary bearing 47 surrounding the sleeve. When the link rod 5 is pressed upward by the operating member, the lever 6' turns about the sleeve 9', so that the link 19', if coupled to the lever 15', causes the latter to lift the presser foot bar. On the other hand, if the operating member is actuated to lift the rod 5, after the link 19' has been swung over into the position indicated by dotted lines in Fig. 4, wherein the shoulder 19a is in engagement with the projection 44, the link 19' will entrain the sleeve 9', when it is swung by the lever 6' about the center of the shaft 8', the spring 43 being thus tensioned. The sleeve 9' entrains in turn the shaft 8' over the friction coupling 40, by means of which shaft the width of the seam is regulated. After the operating member has been released upon such a movement of adjustment, the sleeve 9' is turned back into the initial position with the aid of the return spring 43.

What we claim is:

1. A control means for zig-zag sewing machines 30 having a presser foot, a lifting mechanism for the presser foot and an oscillatory needle operating mechanism, comprising an operating member adapted to be actuated by the knee of the operator, and a coupling member adapted to couple the operating member at will alternatively to the presser foot lifting mechanism and to the needle operating mechanism to enable lifting of the presser foot or adjustment of the needle amplitude by the knee.

2. A control means for zig-zag sewing machines 40 having a housing, a presser foot, a lifting mechanism for the presser foot, an oscillatory needle operating mechanism comprising a shaft journaled in the housing, an operating member adapted to be actuated by the knee of the operator and comprising a bell crank lever journaled coaxially with said shaft, and a coupling member for cooperation with said lever to connect the lever with the presser foot lifting mechanism or with the shaft alternatively at will, whereby the presser foot may be lifted or the amplitude of the oscillatory needle may be adjusted at desired moments.

3. A control means as claimed in claim 2 in which the coupling member comprises a carrier pivoted to the bell crank lever and provided with abutments, and in which a flange is attached to the shaft and has a recess, and the presser foot lifting mechanism comprises an arm rotatably mounted on the shaft and having a slot formed therein, one of said abutments being adapted to be engaged with the recess and another of the abutments being adapted to cooperate with the slot of the arm.

4. An operating device for zig-zag sewing machines comprising an operating member adapted to be actuated by the knee of the operator, mechanisms adapted to be operated by said operating member, a coupling means adapted to connect the operating member with said mechanisms alternatively at will, said coupling means comprising a supporting member and a link pivoted at one end to said supporting member and adapted to be engaged selectively with one of 70 75 said mechanisms.

5. A control means for zig-zag sewing machines having a housing, a presser foot lifting mechanism comprising a lever pivoted to the housing and an oscillatory needle operating mechanism, comprising means to adjust the amplitude of the needle operating mechanism, said means comprising a shaft, a bushing or sleeve rotatably journaled in the housing and having a projection and means to connect the bushing with the shaft, an operating device for selective operation of said mechanisms, said device comprising a supporting member and a hook-shaped link pivoted to said supporting member at its one end and adapted to be connected with one end of said lever or to be turned over and disengaged with said lever 15 end to engage the projection on the sleeve or bushing.

6. A control means as claimed in claim 5 having abutments on the rotatable sleeve, corresponding to fixed abutments for determining an initial position of the operating device, and a restoring spring connected with the sleeve to keep the same resiliently in its initial position. 20

7. In a zig-zag sewing machine having a hous-

ing, a presser foot lifting mechanism and an oscillatory needle operating mechanism, means to adjust the amplitude of the needle operating mechanism, comprising a shaft journaled in the housing, a sleeve rotatably mounted on said shaft, an operating device adapted to be actuated by the knee of the operator, a coupling member for alternative connection of said device with said lifting mechanism and said sleeve, and a friction clutch cooperating with the shaft and sleeve to transmit operating motion from the sleeve to the shaft.
